ABRADING MACHINE

Augustus J. Paulson, Trevose, Pa.

Application November 27, 1945, Serial No. 631,027

4 Claims. (Cl. 51—134)

1

My invention is an abrading machine which is primarily designed for grinding the faces of cutting or biting edges of teeth of power driven chain-saw links, such biting edges being preferably ground at acute angles to ground peripheral or trailing edges of such teeth. As such chain-saws generally comprise sets of pivotally connected links having some of their teeth bent laterally with respect to the plane of the link body, and hence with respect to the plane of the kerf, my improved machine is preferably adapted to receive and grind links having teeth bent at various angles, and to this end various types of work-supporting seats may be substituted for one another in the machine.

By my improvements, the biting edges of such saw teeth may be ground accurately and rapidly by an abrasive face of a rotating cup wheel of substantially constant diameter, and the abrasive face of the grinding wheel may be frequently dressed without interrupting the production of ground links.

In the preferred embodiment of my invention, a rotatable abrasive wheel and a rotatable work holder are mounted to rotate about parallel axes and the wheel and holder are axially adjustable so as to bring a radial face (as distinguished from a peripheral face) of the abrasive wheel into engagement with the tooth of a link held by the work holder.

The work holder preferably comprises a wheel or disk having peripheral sockets for receiving various types of seats on which various types of chain links may be held for grinding. Each of the various types of seats has a substantially radially extending surface with one or more work locators projecting therefrom. A spring biased pressure clamp rocking on an axis substantially parallel with the axis of the work holder presses a work piece against such radial seat so as to hold the biting edge of the tooth to be cut substantially radially with respect to the axis of the work holder.

Preferably each clamp is spring biased to yieldingly hold a work piece against a radial seat during the grinding of the tooth, and is positively rocked away from the seat before and after the grinding of a tooth to permit the insertion and discharge of work pieces.

The positively acting clamp-rocking mecha-

2

nism preferably comprises a series of plungers normally biased away from the clamps and a complementary series of axially movable cams which are operated by the engagement thereof with a pair of fixed cam members having spaced tapered ends.

The rotatable work holder also carries a dressing tool, such as a diamond point, for dressing the abrading face of the grinding wheel on each revolution of the work holder; the diamond point preferably lying at a greater distance than the work piece seats from the center of the tool holder.

The characteristic features and advantages of my improvements will further appear from the following description of a preferred embodiment of my invention and the accompanying drawings in illustration thereof.

In the drawings, Fig. 1 is a top plan view of a grinding machine embodying my invention; Fig. 2 is a front elevation of the revolving work holder and its support taken on the line 2—2 of Fig. 1 but with the grinding wheel omitted; Fig. 3 is an irregular sectional view of the work holder and its stand taken on the line 3—3 of Fig. 2; Fig. 4 is a rear elevation of a stripped work holder wheel; Fig. 5 is a top plan view of the stripped work holder wheel shown in Fig. 4; Fig. 6 is a face view and Fig. 7 is a side view of a work piece seat; Fig. 8 is a plan view and Fig. 9 is an edge view of a work piece clamp; Fig. 10 is a plan view and Fig. 11 is an edge view of a clamp bracket; Fig. 12 is a detached detail view of a clamp biasing spring; Fig. 13 is an end view and Fig. 14 is a longitudinal view of a clamp-rocking plunger; Fig. 15 is a detached detail view of a coiled spring for biasing the plunger away from the clamp; Fig. 16 is an edge view and Fig. 17 is a plan view of a plunger guide ring and retainer; Fig. 18 is an end view and Fig. 19 is a longitudinal view of a cam slide for operating the plunger; Fig. 20 is an edge view and Fig. 21 is a face view of a closure for the cam slideway; Fig. 22 is an end view and Fig. 23 is a longitudinal view of a dressing tool; Fig. 24 is an end view and Fig. 25 is a longitudinal view of a dressing tool post; Fig. 26 is an end view and Fig. 27 is a longitudinal view of a pintle for hinging the work clamp on its bracket; Fig. 28 is a top plan view and Fig. 29 is an end view of a work holding seat plate which

may be substituted for the seat plate shown in Figs. 6 and 7; and Fig. 30 is a face view and Fig. 31 is an edge view of one type of chain-saw link, such as are ground on my machine when the latter is equipped with plates such as shown in Figs. 6 and 7.

In the embodiment of my invention illustrated in the drawings, a bed plate 1 has slidably mounted thereon a housing 2 which is adjustable by means of a hand wheel 3 and screw 4 journalled in a bearing 5. A cup shaped abrasive wheel 6 is fixed on the end of a shaft 7 journalled in the housing 2 and rotated by a source of power, such as an electric motor (not shown). The grinding wheel 6 is thereby rotatable by the shaft 7 about an axis parallel with the direction of movement of the housing.

A stanchion 8 projects upwardly from the bed 2 in laterally and longitudinally spaced relation to the housing 2 and has journalled therein a shaft 9 which is connected through the flexible coupling 10 with the shaft 11 of a gear box 12 of an electric motor or other source of power 13.

The front face of the stanchion has fixed thereto two diametrically disposed cam members each comprising a curved bar 14 or 14' projecting from the face of the stanchion and having a flat intermediate surface and beveled end surfaces 14a, 14b and 14c, 14d respectively tapering down to the plane of the face of the stanchion.

The end of the shaft 9 projects forward from the face of the stanchion 8 and has bolted thereto a work holder which is rotatable about an axis parallel with, but offset from, the axis of the grinding wheel 6 for advancing work pieces, such as chain-saw links A, one at a time into position for engagement by the abrasive face of the rim of such grinding wheel.

The work holder preferably comprises a wheel or disk 15 having a periphery containing equidistant recesses 16 each having front and back walls of unequal height. The lower front wall of each recess has a flat surface 17 projecting forward therefrom along a line intersecting to the periphery of the wheel 15. A countersunk socket 18 projects radially inward from each of these flat surfaces 17 and each socket 18 has its inner end intersected by an axially extending aperture, forming a slideway 19.

Each recess 16 forms an axial groove adapted to receive the foot of an L-shaped seat plate, such as 20 or 20'; the seat plate appropriate for the work to be done being secured to the bottom of the groove by a screw. The longer leg of the seat plate extends radially relatively to the axis of the wheel 15 and the outer edge of such radial leg contains a notch 21 or 21' with a beveled bottom 22 or 22'. Work locator pins 23 or 23' project normally from the face of the radial leg of the seat plate 20 or 20'; the face of such leg being substantially coincident with a radius of the work holder.

A bracket 24 is screwed to each flat surface 17 and has a clamp 25 hinged thereto by the bolt 25'. The clamp 25 is normally biased by a spring 26 toward position for clamping a work piece against the radial surface of the seat plate 20 or 20'.

Each socket 18 contains a headed plunger 27 which is normally biased inwardly and away from the adjacent clamp 25 by a coiled spring 28 bearing against the guide ring and stop 29 fixed in the counterbore of the socket 18.

Each plunger 27 is movable longitudinally against the biasing action of its spring 28 by a screw 4.

cam slide consisting of a notched cylindrical shaft 30 which is normally positioned to permit seating of the tapered head 27' of the plunger 27 in the notch 30' of the slide 30. One end of the aperture 19 is closed by a disk 32 to prevent the ejection of the slide 30.

The tapered noses of the slides 30 project from the rear face of the work holder wheel 15 into the planes of the cam segments 14 and 14' which are of sufficient height to shift the notches 30' beyond the heads 27' when the noses of the respective shafts 30 engage the respective fixed cams 14 and 14'. Each cam 14 or 14' is engaged by the same number of slides 30 at any time, and when a slide 30 is ascending an acclivity of one cam another slide 30 is descending the declivity of the other cam so as to maintain balance and avoid chattering and vibration.

A variety of work seat plates similar to the plates 20 and 20' may be provided, each type of plate having a vertical face so inclined as to appropriately position a type of link having its tooth bent laterally at a desired angle. Preferably all the recesses 16 contain plates of the same type at any one time, but, if desired, different type plates may be mounted in successive grooves 16 to permit sequential grinding of the different types of links required for forming a chain section.

The work holder wheel 15 contains a radial socket 34 in which is secured a tool post 35 having a seat 36 for a dressing tool 37, which may be clamped in position by a suitable set screw.

In the operation of the machine, a feeder may be positioned at the left of the machine (Fig. 1) to lay a link, such as A, upon each seat plate, such as 20, with the apertures in the link in registration with the locator pins 23. The link or work piece is placed on a particular plate while the clamp 25 appurtenant to the particular seat being filled is opened by its plunger 27, due to the movement of such plunger by the engagement of its complementary slide 30 with a cam segment 14. The link A is so positioned by the locator pins 23 that the beveled notch 21' in the plate will provide clearance for the grinding wheel 6 when the work holder is turned clockwise into position for cutting the edge —a— of the link.

As the loaded seat 20 reaches the apex of its rotation, the slide 30 slides down the tapered surface 14b of the cam 14 and the slide 30 is moved longitudinally by the pressure of the plunger 30 until the notch 30' registers with the head 27', thereby permitting the plunger 27 to recede and the spring 26 to bias the clamp 25 into position to securely lock the work piece A against the seat plate 20.

As the work piece or link A passes the wheel 6, the edge —a— is accurately ground by the face of the abrasive wheel 6. After the work piece A has passed the wheel 6, the nose of the slide 30 engages the acclivity 14c of the cam segment 14', thereby shifting the shaft 30 longitudinally to engage the normal periphery thereof with the plunger 27 and shift the latter longitudinally to open the clamp 25. The work piece A then falls clear of the locator pins 23 and as the rotation of the wheel 15 continues, the work piece falls from the work holder.

On each revolution of the work holder 15, the dressing tool 37 contacts the abrasive face of the wheel 6 and accurately dresses it without interfering with production, since wear of the wheel 6 may be compensated for by the adjusting screw 4.

Having described my invention, I claim:

1. An abrading machine comprising a rotatable abrasive wheel in a rotatable work-holder positioned for moving work-pieces into engagement with a face of said wheel, said holder having a series of work-locator pins each extending substantially normal to a radius from an axis of rotation of said work-holder, and a clamp fulcrumed on an axis substantially parallel with said axis of rotation, said clamp having a body the length of which is substantially equal to the distance between its axis and the face of a work-piece on said holder, said body terminating in an end portion farthest from said axis with said end portion having a surface in a plane normal to the length of said body, said clamp being movable into position about said axis so that the length of the body and the length of said locator pins are substantially parallel and the end surface engages the work-piece.

2. A work holder for an abrading machine comprising a rotatable wheel having a series of radially extending seats for work pieces, a clamp adjacent to each of said seats and rocking on an axis parallel to the axis of rotation of said wheel, for holding a work piece thereon, and means for rocking said clamps and comprising a set of plungers and a complementary set of shafts movable transversely to said plungers.

3. A work holder for an abrading machine comprising a rotatable wheel having a series of radially extending seats for work pieces, a rocking clamp adjacent to each of said seats for holding a work piece thereon, a spring biasing each clamp toward work holding position, and means for rocking said clamps away from work holding position and including a series of plungers, a complementary series of cam shafts movable parallel with the axis of rotation of said holder, and a stationary cam engageable by said shafts to shift said shafts longitudinally.

4. An abrading machine comprising a rotatable abrasive wheel and a rotatable work holder positioned for moving work pieces into engagement with a face of said wheel, said wheel being mounted in a support on one side of said work holder and having a radial abrading surface axially movable toward work on said holder from the support side thereof, said holder having a series of peripheral work clamps rocking on axes parallel with the axis of rotation of said holder and means for rocking said clamps including a ring segment having a radial faced cam spaced from the side of said work holder on the side thereof remote from said support and slides projecting laterally from said work holder and engaging a lateral face of said ring segment.

AUGUSTUS J. PAULSON.
